BOILER CASING

Thomas C. Ervin, Houston, Tex.

Application December 28, 1933, Serial No. 704,353

7 Claims. (Cl. 122—494)

The objects of the present invention are to provide an insulating casing for boilers, which can be readily applied or removed, which will be effective as an insulation and protection for the boiler, which will be durable and lasting and which can be made up at a reasonable cost and shipped out from the place of manufacture in a form ready to be applied to boilers then in service.

These and other desirable objects are attained by the novel features of construction, combinations and relations of parts hereinafter described, illustrated and broadly covered in the claims.

The drawings accompanying and forming part of the specification illustrate practical and preferred embodiments of the invention, but it is to be understood that the structure may be modified and changed all within the true intent and broad scope of the invention.

Fig. 1 is a side elevation showing the invention as applied to a boiler of typical form.

Fig. 2 is an end view, on a larger scale looking at the firebox end of the boiler.

Fig. 3 is a vertical sectional view of the casing as on substantially the plane of line 3—3 of Fig. 1.

Figs. 4, 5, 6, 7, and 7a are broken enlarged sectional views substantially as on lines 4—4, 5—5, 6—6, 7—7 and 7a—7a of Fig. 1.

Fig. 8 is a horizontal sectional view of the dome covering portion of the casing as on line 8—8 of Fig. 1.

Fig. 9 is an interior view of one of the dome half covers.

Fig. 10 is an interior perspective view of the left hand top cover section for the wagon top.

Figs. 11 and 11a are fragmentary detail views illustrating a special form of anchorages for the screen or webbing that holds the insulation within the cover plates.

Fig. 12 is a broken horizontal sectional view of the wagon top side and throat sheet cover sections, substantially as on line 12—12 of Fig. 3.

Fig. 13 is an interior view of one of the throat sheet cover sections.

Fig. 14 is a broken detail of the hook construction for coupling opposite sections together before the banding straps are applied.

Fig. 15 is a broken detail of the tightening means for the straps or bands.

In the form of the invention herein disclosed, the casing is made up of sections which meet in overlapping relation, along the top, the sides and at the bottom of the boiler. These further

are divided into front and middle course barrel cover sections and wagon top cover sections.

The front, top barrel cover sections are designated 17; and the front lower barrel cover sections 18; the top middle course sections 19; the lower middle course sections 20; the upper wagon top sections 21 and the side wagon top sections 22. The throat sheet cover sections are designated 23 and the dome half cover sections 24.

These sections, for an average boiler, are of a practical and convenient size for manufacture and shipment and while light enough for easy handling are sufficiently rigid and firm for all practical purposes.

The various cover sections are alike, in that each consists of a hollow self-supporting shell containing a blanket of insulating material. Similar reference characters therefore are here used in describing these various cover units.

Each cover unit consists of a cover sheet 25, outlined to that part of the boiler to which it is to be applied and held to the approximate shape of that portion of the boiler by ribs or internal flanges 26, about the edges of the same. These inwardly extending flanges in addition to giving form to the sheet covering, provide the hollows within the sheet, receiving the insulating material 27. Mineral wool or the like, may be used as the insulating material. To hold such insulation in place, expanded metal lath 28, woven wire fabric, or the like, is laid over the same and welded or otherwise secured at its edges to the retaining flanges 26. This screen or open-work retainer may be supported and kept from sagging by intermediate strips or ribs 29, laid over the same, in general parallelism to the sheet and welded or otherwise secured to the edge flanges as indicated at 30, Figs. 10 and 13.

Instead of the retaining ribs 29, the insulation holding fabric may be secured at intermediate points by short studs or wires 31, shown in Figs. 11 and 11a, as welded to the inner surface of the sheet at 32, and as extending through the insulation and the wire fabric and clinched over the latter at 33.

The insulation holding and supporting wire fabric forms a parallel reinforcement to the cover sheet and, with the interposed layer of insulation, materially reinforces and stiffens the structure, so that it may be readily handled as a unit.

To make the casing waterproof, the joints between cover sections are lapped, where required, by flanges 34, of one section overlying the edges of an adjoining section. These overlapping flanges may be provided as particularly shown in

Figs. 5, 6, 8 and 10, by setting the internal reinforcing flanges 26, back from the edges of the cover sheets a desired distance and then outwardly offsetting such projecting material as indicated at 35, Figs. 5 and 6, so that such projecting edges will readily slip over and closely hug the adjoining edges of the next sections.

The cover sections are provided with suitable openings for passing structural parts or fittings of the boiler. Thus, the front barrel sections 17, 18, have the registering recesses 36, in their meeting edges for feed water connections, Fig. 1, the upper wagon top sections 21 and throat sections 23, have recesses 37, for steam fittings, the dome half cover sections have meeting recesses 38, 39, in their side and top edges for steam connections. For steam dome, manhole and handhole purposes, openings 40, 41, 42, are provided in the middle course sections 19, barrel sections 17, wagon top and throat sections 21, 23, and these in each case are lined with flanges 43, corresponding in effect to the manner in which the edge flanges 26, are indented to form the recesses 36, 37, 38, 39.

The manhole and handhole openings are closed by removable covers 44, 45, shown as fitted over the manhole and handhole bolts 46, 47, and as detachably held by the extra nuts 48, 49, engaged on the projecting portions of said bolts, Figs. 4 and 6.

The cover sections are secured in their cooperating overlapped relation on the boiler by encircling bands or straps 50, overlapped at their ends as indicated at 51, Fig. 15, and adjustably held together by bolt fastenings 52, engaged with angles 53, on the opposite end portions of the straps.

In some instances, or in some places, the sections may be secured together by bolts 54, passed through outstruck lugs or flanges 55, as shown for the wagon top sections in Figs. 1, 2 and 10.

Primarily, as an aid in assembly, the cooperating or companion sections may have interengaging portions which will hook together and partly hold the sections while the securing bands are being located and adjusted. This feature is shown particularly in Figs. 10 and 14 where hooks 56, are shown struck out from the flange 26, at the edge of one section to pass through and interlock with slotted portions 57, in the edge flange of the adjoining section. When so engaged, the overlapping flanges 34 of the sections will hold them in this relation, it being noted that after passing through the slots, the hooks will be shifted into interlocking relation, as the cover sections are brought into proper alignment.

A special feature, illustrated particularly in Figs. 1, 3, 4 and 5, is that the casing is supported with a small air space 58, between the insulation and the boiler, which materially increases the effectiveness of the insulation and also eliminates the possibility of any corrosive action between the insulation and boiler plates. This spacing of the casing out of contact with the plates is effected by resting it on the projecting rivet heads 59, of the boiler shell, the insulation retaining mesh 28, engaging these rivet heads and supporting the cover sections off the boiler and with but a minimum thermal conducting relation between the boiler and cover sections. The showing of the boiler in Fig. 3 is incomplete, only the outline of the same being indicated for the purpose of illustrating the air jacket.

For positioning and securing purposes, the front end flanges of the barrel sections 17, 18, may be extended inward to meet the smoke box portion

of the boiler as at 60, Fig. 7, and the rear end flanges of the wagon top sections may be extended inwardly as at 61, Figs. 2 and 4, over the firebox end of the boiler. Also, the front end flanges of the side wagon top sections 22, may be extended inwardly as at 62, Figs. 3 and 12, over the front end of the firebox and lapped over the throat sheet sections 23, to aid in holding the latter in position. The lugs 55 on the wagon top and throat sheet sections may be formed as integral outturned ends of these widened flanges 61 and 62, substantially as indicated.

The cover sections are readily cut, shaped and assembled from stock materials and when made up, constitute each a firmly braced insulating blanket section, which can be shipped to the location of a boiler and applied without disturbing the boiler or its various connections. In case of necessity, any or all sections may be readily removed and the casing as a whole may, if desired, be successively used on different boilers. The casing is tight against the weather and specially adapted for outdoor or unprotected boiler installation. The insulation may be of any desired thickness, but because of the air space provided between the insulation and the boiler surface, it need not be so heavy for equal insulating results as if it were in direct contact with the boiler shell. The casing is strong and rugged enough to stand vibration and rough usage, such as encountered in the oil fields where protection of this character is particularly required. In the form illustrated, there are only sixteen cover sections, four quarter segments for the front barrel portion, four quarter sections for the middle course, two top quarter sections and two side sections for the wagon top, two segments for the throat sheet and two half sections for the dome. The rearwardly projecting flanges of the front sections overlap and hold the front edges of the middle course sections, the front edges of the wagon top side sections overlap and hold the throat sheet sections and the dome sections to an extent overlap and hold the top middle course sections, so that the sections brace and hold each other independently of the encircling bands. The handhole and manhole cover plates also aid in fastening the cover sections down on the boiler shell.

While the practical forms of the invention illustrated are preferred, it will be realized that changes may be made therein within the broad coverage of the claims following.

What is claimed is:

1. A removable and replaceable sectional insulating boiler casing, comprising segmental cover sections lined with insulating material and meeting on longitudinal and transverse lines, longitudinally and transversely extending overlapping flanges on certain of the cover sections covering the longitudinal and transverse joints between the cover sections and bands encircling the segmental cover sections, securing the same together in said longitudinally and transversely overlapped relation, said cover sections having interlocking hook elements at the meeting edges of the same and inside the overlapping flanges between the joints.

2. In combination with a boiler having projecting bolts for handhole covers and the like, a structurally independent sectional insulating casing removably applied over said boiler and having openings for said handhole covers and the like, removable covers for said casing openings engaged over said casing sections and fitted over

said bolts and nuts engaged on said bolts removably securing said casing covers in position over said handhole covers and the like.

3. In combination with a boiler having barrel, 5 wagon top and dome portions, a removable and replaceable sectional insulating casing therefor, comprising top and bottom barrel cover sections, top and side wagon top cover sections and dome cover sections and bands encircling said barrel, 10 wagon top and dome cover sections in covering position on the boiler, said cover sections engaging in abutting relation and companion sections having on abutting surfaces hooks and seats for said hooks, whereby the sections are positively 15 held against separating movements.

4. In combination with a boiler having barrel, wagon top and dome portions, a removable and replaceable sectional insulating casing therefor, comprising top and bottom barrel cover sections, 20 top and side wagon top cover sections and dome cover sections and bands encircling said barrel, wagon top and dome cover sections in covering position on the boiler said cover sections having weather excluding overlapping flanges at the 25 joints between the same, said cover sections engaging in abutting relation and companion sections having on abutting surfaces hooks and seats for said hooks whereby the sections are positively held against separating movements.

5. In combination with a boiler having projecting fittings, a sectional insulating boiler covering applied thereto, certain of said cover sections having openings therethrough for the boiler fittings, covers for said openings and means on said boiler fittings securing said covers in position closing said openings and hold said cover sections in position on the boiler. 5

6. A sectional insulating boiler casing, comprising cover sections having inwardly extending flanges, boiler insulation within said cover sections between said flanges, insulation retaining screen overlying said insulation, straps overlying said screen and secured to said inwardly extending flanges and flanges projecting at the edges 10 of certain of said cover sections and overlapping the edges of adjoining sections.

7. A sectional insulating boiler casing, comprising cooperating insulating cover sections having overlapping edge portions, hooks and 20 keepers for the same on adjoining edges of said cover sections beneath the overlapping edge portions of the same for connecting said cooperating overlapping edge portions to facilitate the placement of same on a boiler and encircling 25 bands for securing and binding together said thus connected cover sections in final position on a boiler.
